United States Patent Office

Des. 196,435
Patented Oct. 1, 1963

196,435

TELEPHONE DESK SET

Paul-Hans Thies and Eduard Merz, Munich, Germany,
assignors to Siemens & Halske Aktiengesellschaft
Berlin and Munich, a corporation of Germany

Filed Oct. 25, 1960, Ser. No. 62,618

Claims priority, application Germany Apr. 28, 1960

Term of patent 14 years

(Cl. D26—14)

Fig. 2.

Des. 196,435

PAGE 3

FIG. 1 is a view of a telephone desk set, showing our new design, as seen from the front;

FIG. 2 is a side view of the telephone desk set, the hand set being omitted;

FIG. 3 is a rear view of the telephone desk set; and

FIG. 4 is a top view thereof.
The legible matter shown in broken lines is for illustrative purposes only. The cord connecting the hand set and the telephone base has been omitted from the drawings for convenience of illustration.

We claim:

The ornamental design for a telephone desk set, as shown and described.
